UNITED STATES PATENT OFFICE.

PERCY B. T. WILLIAMS, OF PHILADELPHIA, PENNSYLVANIA.

DESIGN FOR A NECK-DUSTER BRUSH.

Application filed December 1, 1923. Serial No. 7,932. Term of patent 14 years.

To all whom it may concern:

Be it known that I, PERCY B. T. WILLIAMS, a citizen of the United States, residing in Philadelphia, Pennsylvania, have invented a certain new, original, and ornamental Design for a Neck-Duster Brush, of which the following is a specification, reference being had to the accompanying drawing, in which—

Fig. 2, is a sectional view of the handle thereof.

I claim—

The ornamental design for a neck duster brush, substantially as shown.

PERCY B. T. WILLIAMS.
